(57) **ABSTRACT**

The present applications relates to techniques and equipment
to control the alignment of cut sheets of paper that are
transported in parallel in an inserting system prior to their
assembly into a document and inserted into an envelope. The
alignment of the parallel sheets is adjusted by commanding
incremental position changes to servo drive motors used to
control the position of the parallel sheets during their
transport through a hold module of the inserting system.

**METHOD AND SYSTEM FOR
SYNCHRONIZING ITEMS USING POSITION
COMPENSATION**

RELATED APPLICATIONS

This application claims the benefit of U.S. Provisional Application No. 61/903,734 entitled "METHOD AND SYSTEM FOR SYNCHRONIZING ITEMS USING POSITION COMPENSATION" filed on Nov. 13, 2013, the disclosure of which is entirely incorporated herein by reference.

TECHNICAL FIELD

The present subject matter relates to techniques and equipment to control the alignment of sheets of paper that are assembled into a document before the document is inserted into an envelope by mail processing equipment, such as an inserter system.

BACKGROUND

U.S. Pat. No. 6,443,447 B1, entitled "Method And Device For Moving Cut Sheets in a Sheet Accumulating System" and U.S. Pat. No. 7,752,948 B2, entitled "Method and Apparatus for Enhanced Cutter Throughput Using an Exit Motion Profile", both address sheet alignment by having a velocity motion profile. A first path's initial speed is greater than an adjacent second path until it is determined that it must be decelerated to the adjacent second path's speed to be delivered to the downstream module at the desired lead edge to lead edge distance/offset.

U.S. Pat. No. 6,764,070 B2, entitled "Path Length Compensation Method and Device for High Speed Sheet Cutters" addresses sheet alignment by increasing the path length at which one document must travel such that the lead edge to lead edge distance/offset is at the desired amount upon entering a Turnover Sequencer (TOS)/Right Angle Turn (RAT).

The existing technology does not address the requirement for positive control of both the left and right sheets' alignment being adjusted in position relative to each other. In addition, existing technology does not account for the initial alignment of the sheets as received from an upstream module.

Current sheet synchronization systems only adjust relative position of the side by side sheets to account for the path length difference that the sheets experience when traveling through the turnover sequencer (TOS). This synchronization is accomplished by using a different velocity motion profile for each sheet. The velocity profile must include an acceleration and deceleration rate that does not cause paper damage or slippage in the sheet drive. The steady state velocity must be maintained between the acceleration and deceleration period such that the total motion profile for each sheet produces the desired overlap of the sheets upon output from the TOS. The total motion profile is a complex command sequence. The total motion profile configuration only accounts for the TOS path length difference and cannot account for the amount of offset between the sheets that results from the cutting and advancement of the sheets out of the cutter.

Hence a need exists for measurement of the sheets initial alignment upon reception from an upstream module and for using separate servo motor position control for both the left

and right sheets to employ a sequence of position control adjustments to each sheet during the sheet transition through the hold module.

SUMMARY

The teachings herein alleviate one or more of the above noted inserter problems with the use of a device such as photocells of a hold module to capture the angular displacement of servo motors for each parallel sheet transport which are configured to transport sheets as they exit a cutter module of an inserting system. These values are used to determine the initial alignment of the sheets. The alignment of the sheets is adjusted by commanding incremental position changes to the servo drives which control the position of the sheets during their transition through the hold module.

In certain aspects, there is provided a an inserting system configured to adjust alignment of a plurality of sheets of paper outputted from a cutter module. The inserter system includes a hold module positioned downstream from the cutter module. The hold module includes a plurality of parallel sheet transports for transporting the sheets of paper in parallel. A plurality of servo motors are configured to drive each sheet transport and each servo motor including an encoder configured to generate encoder pulses for each rotation of the servo motors. First and second photo sensors are configured to detect a presence of first and second sheets at respective sheet transport entry points. An inserter system control computer is programmed to calculate an alignment adjustment of the sheets in the hold module to account for requirements of one or more modules downstream of the hold module. The system control computer is configured to calculate an initial alignment offset between the sheets based on a difference in encoder pulses received between a first detection of the first sheet by the first photo sensor on a first sheet transport and a detection of the second sheet by the second photo sensor on a second sheet transport; receive established sheet alignment requirements of the one or more modules downstream of the hold module; calculate an alignment correction distance, and control a distance that each sheet in the hold module is to be moved for each cyclic update.

In certain other aspects, there is provided a method for aligning a plurality of sheets processed in parallel by an inserter system. The method includes transporting first and second sheets through parallel first and second transports of a hold module of the inserter system. Photocell triggers are received from first and second photocells, and encoder pulse values are received from first and second encoders that are positioned at the first and second transports in the hold module as the first and second sheets are transported through the hold module. An initial alignment offset is calculated by counting a number of encoder pulses received from the first encoder from a first time at which the first sheet triggers the first photocell until a second time at which the second sheet triggers the second photocell. An amount of alignment correction is divided equally between a first servo motor associated with the first transport path and a second servo motor associated with the second transport path based on requirements of one or more subsequent modules downstream from the hold module. The first servo motor is driven to adjust a first distance moved by the first sheet in the first transport path for each cyclic update, and the second servo motor is driven to adjust a second distance moved by the second sheet in the second transport path for each cyclic update. A total number of cyclic updates sent to each servo

motor results in moving the first and second sheets through the hold module while imparting an offset distance between the first and second sheets.

The advantages and novel features are set forth in part in the description which follows, and in part will become apparent to those skilled in the art upon examination of the following and the accompanying drawings or may be learned by production or operation of the examples. The advantages of the present teachings may be realized and attained by practice or use of the methodologies, instrumentalities and combinations described herein.

BRIEF DESCRIPTION OF THE DRAWINGS

The drawing figures depict one or more implementations in accord with the present teachings, by way of example only, not by way of limitation. In the figures, like reference numerals refer to the same or similar elements.

FIG. 1 is an exemplary block diagram of an inserter configured to process mailpieces.

FIG. 2 is an exemplary isometric view of the inserter modules used to process multiple sheet documents.

FIG. 3 is an exemplary isometric view of the turnover sequencer used to merge sheets of a document.

FIG. 4a is an exemplary isometric view of the hold module used to align sheets for processing in subsequent modules of an inserter.

FIG. 4b is an exemplary isometric view of the hold module as viewed looking toward the input section from the output section.

FIG. 5 is an exemplary diagram of the sheet positions as they move through the hold, TOS entry transport and TOS with zero initial alignment and without position adjustment.

FIG. 6 is an exemplary diagram of the sheet positions as they move through the hold, TOS entry transport and TOS with zero initial alignment and position adjustment for TOS path length difference.

FIG. 7 is an exemplary diagram of the sheet positions as they move through the hold, TOS entry transport and TOS with initial alignment and position adjustment for TOS path length difference.

FIG. 8 is an exemplary diagram of the sheet positions as they move through the hold, TOS entry transport and TOS with position adjustment accounting for initial alignment and TOS path length.

FIG. 9 is an exemplary diagram of the sheet positions with initial alignment due to the cutter as they approach hold module input photocells.

FIG. 10 is an exemplary diagram of the sheet positions as the right sheet reaches the right photocell.

FIG. 11 is an exemplary diagram of the sheet positions as the left sheet reaches the left photocell.

FIG. 12 is an exemplary diagram of the sheet positions as they transition through the hold and each sheet receives an incremental position adjustment.

FIG. 13 is an exemplary diagram of the sheet positions after the hold position adjustments have been completed.

FIG. 14 is an exemplary process flow chart.

FIG. 15 illustrates a network or host computer platform, as may typically be used to implement a server.

FIG. 16 depicts a computer with user interface elements, as may be used to implement a personal computer or other type of work station or terminal device.

DETAILED DESCRIPTION

In the following detailed description, numerous specific details are set forth by way of examples in order to provide

a thorough understanding of the relevant teachings. However, it should be apparent to those skilled in the art that the present teachings may be practiced without such details. In other instances, well known methods, procedures, components, and circuitry have been described at a relatively high-level, without detail, in order to avoid unnecessarily obscuring aspects of the present teachings.

The description of the FIGS. 3 through 14 utilizes nomenclature to reference the numerous parameters associated with the position and distance traveled for the sheets of paper being processed in the hold module 106. Table 1 below is a cross-reference of the nomenclature used in the drawings to the definition of the parameter. The sheet processing associated with the hold module illustrates an exemplary process for aligning a left sheet S1 and a right sheet S2. The dash numbers 1 through 4 assigned to sheet references (S1 and S2) indicate the position in the process cycle in which the sheet is located. Multiple dash references for the same sheet (S1 or S2), which are used in the same figure, are for illustration of the process cycle where several process cycle steps are shown in one figure.

TABLE 1

	Nomenclature
O-I	Initial overlap—The amount which the left and right sheet will overlap at the TOS exit if sheets are perfectly aligned at the TOS entry
O-D	Desired overlap—The desired amount for the left and right sheet to overlap at the TOS exit
A-I	Initial alignment—The distance parallel to the paper path between the left and right sheets lead edge upon reception from upstream module
A-F	Final alignment—The distance, parallel to the paper path, between the left and right sheet's lead edge prior to entering the TOS necessary to get the desired overlap (O-D) at the TOS exit
A-C	Alignment Correction—The amount to adjust the left and right sheet's alignment, given an initial alignment A-I, to get final alignment A-F prior to the TOS entry transport
D-C	The distance both hold module servo drives commanded position is incremented each cyclic fieldbus update to maintain constant velocity
N	The number of cyclic fieldbus updates which will occur during the time which it is possible for adjustment to occur.
D-A	The amount to change the constant velocity increment (D-C) of each servo drives commanded position during adjustment.
D-R	The distance the retarding sheet's servo drive commanded position is updated during adjustment per cyclic fieldbus update.
D-L	The distance the advancing sheet's servo drive commanded position is updated during adjustment per cyclic fieldbus update.
S1-1	Left sheet position at hold module entry for a left hand TOS
S1-2	Left sheet during alignment adjustment in hold module
S1-3	Left sheet in TOS entry transport ready for entry into TOS
S1-4	Left sheet position after exiting TOS
S2-1	Right sheet position at Hold Module entry
S2-2	Right sheet during alignment adjustment period in Hold Module
S2-3	Right sheet in TOS entry transport ready for entry into TOS
S2-4	Right sheet after exiting TOS

Reference now is made in detail to the examples illustrated in the accompanying drawings and discussed below. FIG. 1 illustrates an exemplary block diagram for a mailpiece inserter system 100. The inserter system 100 assembles a mailpiece by accumulating sheets of a document, adding inserts, stuffing the document and inserts into an envelope and collecting the finished mailpieces for delivery to the postal authority. It is understood that inserter system 100 may be configured using alternative designs and still employ the technology disclosed herein. By way of example, inserter system 100 can be configured to include a right hand Turnover Sequence (TOS) and benefit from the disclosures herein. Inserter system 100 is configured to

process 2-up sheets for creating a document, such as but not limited to a financial statement, invoice, advertisement, investment portfolio or prospectuses. The term 2-up refers to the roll of pre-printed paper or stack of pre-printed fan folded sheet paper **101** where two sheets are printed side by side on the roll of preprinted paper or on the stack of preprinted fan folded sheet paper **101**. The dotted line **102** represents where the longitudinal first cut is performed whether the input paper is a roll or sheet. The dotted line represents a cut line and is not an indication that it is perforated. The horizontal cut performed by the cutter module **104** completes the separation of the two sheets from the roll or fan fold stack at which time they are transported to the hold module **106**. Initially, before the horizontal cut, the two sheets are aligned exactly side by side, however due to the method employed to cut and transport the sheets to the hold module the cutter module **104** may output the two sheets with one leading or trailing the other. The hold module **106** measures this initial alignment and accounts for it in the process of adjusting the sheet alignment to be consistent with requirements of the downstream modules. The sheet alignment process disclosed herein is applicable to processing larger width input paper, such as but not limited to, 3-up and 4-up configuration input paper configurations.

In the inserter system **100**, the hold module **106** adjusts the sheets' alignment prior to entering the Turnover Sequencer (TOS) entry transport **107**. The TOS entry transport **107** moves the two sheets from the hold module **106** into the TOS **108**. The cut sheets of paper that make up the document move through the inserter in the direction indicated by arrow **10**, as shown in FIG. 1.

The TOS **108** (FIGS. 1, 2 and 3) merges sheets **S1-3** and **S2-3** (FIG. 3) which are entering the TOS from the TOS entry transport **107**. The TOS illustrated in FIGS. 1, 2 and 3 is a left hand 90 degree turn module. As illustrated in FIG. 3, sheets **S1-3** and **S2-3** are in an offset position, when entering into the TOS **108**, where the sheets enter the left **156** and right **155** open turnover tubes. These tubes are approximately one half open so that when sheets **S1-3** and **S2-3** are driven into the tubes they will curl on the inside surface. The curling action inverts each sheet and redirects them 90 degrees to the left in the direction of the TOS output transport **109**. The TOS turnover tubes **156** and **155** are spaced apart by a distance **157** that corresponds to the width **158** of the sheet. This geometry makes the path length that sheet **S2-3** travels longer than the path length for sheet **S1-3** by a distance equal to the sheet width **158**. Sheet **S2-4** is on top of sheet **S1-4** after they exit the TOS **108**. In order to have the merged sheets **S1-4** and **S2-4** overlapped by distance (O-D), as required for downstream processes, they must enter the TOS with lead edge to lead edge offset by a distance (A-F). The hold module's design for adjusting the alignment of two side by side sheets, to obtain the desired overlap distance (O-D), is explained below with reference to FIGS. 9 through 14.

Referring back to FIGS. 1 and 2, the TOS output transport **109** moves the merged sheets **S1-4** and **S2-4** from the TOS **108** to the accumulator **110**. The accumulator **110** collects all the sheets that form the pages of a document before passing the completed document to the folder **112**. The folder **112** imparts the fold style required by the particular type of envelope used. The folder **112** may be bypassed if flat envelopes are used. The folder **112** outputs the document to the folder output transport **114** where the document is collected in the collector **118** at the input to the base assembly track **116**. One or more insert feeders (IFS1 . . . IFSN) **120** are located on the base assembly track **116** to add

inserts to the material as the material for the mailpiece is moved down the base assembly track. This material, document plus inserts, is inserted into an envelope by the envelope stuffing station **122**. The required envelopes are drawn from the envelope hopper **124** as needed by the envelope stuffing station **122**. Insert material moves in direction **20** in this section of the inserter **100**. The completed envelope, mailpiece, is moved by the delivery section **126** to the end conveyor **128** where the mailpieces are collected for delivery to the postal authority. The stuffed envelopes are moved in direction **30**. FIG. 2 is an isometric view of the inserter hold module **106** through the accumulator **110** which is an exemplary illustration of these integrated functions.

The position control system of inserter system's **100** hold module **106** is controlled by an inserter control computer **130**. Movement of the sheets of a document through the hold module **106** are controlled by the servo master controller **135**, which is a software module executed in the inserter control computer **130**. The servo master controller **135** communicates position instructions to the right and left side servo drivers **137** and **136** via a fieldbus connection (FIG. 1). The right and left side servo drivers **137** and **136** send the physical servo motor signals to the right and left servo motors **196** and **195** in the right side **265** and the left side **264** hold module transports, as shown in FIG. 4a. The software sheet position control requirements are defined in relationship to FIGS. 9 through 14. It should be understood that alternate computer processing and communication methods can be selected without impacting the performance of the hold module **106**. Inserter job input parameters are received from the data center processor **131** and job results are sent by the computer **130** back to the data center processor **131**. The data center processor **131** is network connected **132** to other inserters (not shown) and to other processing resources present in a document factory as may be required.

Reference is now directed to FIG. 4a of an isometric view of the hold module **106**. The hold module **106** includes two independently driven transports. The left side transport **264** includes two input bottom belts **281** and **282** that are driven by pulleys (not shown), which are mounted on shaft **261**. Two idler roller assemblies **287** and **288** capture sheet **S1-1** against bottom belts **281** and **282**. As shown in FIG. 4b and viewed from the direction of travel **10**, the left side transport **264** has an input roller assembly containing two additional idler rollers **293** and **294** on a single spring loaded shaft **295**. Located on the shaft **295** is the sheet detection input photocell **252** for the left side transport **264**. Belts **281** and **282** (FIG. 4a) form a nip between the belt and the roller assembly which captures sheet **S1-1** and pulls the sheet into the transport. Similarly, the right side transport **265** has an input roller assembly containing two additional idler rollers, **297** and **298** on a single spring loaded shaft **296**. Located on the shaft **296** is the sheet detection input photocell **253** for the right side transport **265**. Belts **284** and **286** (FIG. 4a), form a nip between the belt and the roller assembly which captures sheet **S2-1** and pulls the sheet into the transport.

A third set of idler assemblies **271** and **272** continue the positive transport control of sheet **S1-1** through the hold module **106**. The idler assembly **271** is driven by two rollers (input roller **270** and an output roller—not shown) attached to shafts **262** and **263**. Idler rollers are mounted above the drive rollers to capture sheet **S1-1** and transport the sheet without slippage. Idler assembly **272** is designed to be similar to idler assembly **271**. The left side transport **264** is driven by servo motor **195** (not shown) that is connected to the primary drive pulley **260**. The individual drive shafts

261, 262 and 263 are driven by a drive belt 159 that wraps around the primary drive pulley 260.

The right side transport 265 is driven independently from the left side transport 264 by servo motor 196 (not visible in FIG. 4a). All of the right side transport 265 components are the same as described for the left side transport 264. Shown in FIG. 4a are the bottom belts 284 and 286, two idler roller assemblies 289 and 290 and third set of idler assemblies 273 and 274. The right side transport 265 provides positive transport control of sheet S2-1 through the hold module 106.

The left and right servo motors 195 and 196 are located under left and right side transports 264 and 265 and therefore are not visible in FIG. 4a. The identification arrows 195 and 196 show the approximate position of the servos under the transports. Each servo motor 195 and 196 is driven by a right and left independent servo drives 137, 136 which are controlled by the servo master controller 135 software in the inserter control computer 130 (FIG. 1). Integrated in each servo motor 195 and 196 is a high precision incremental encoder E1 and E2 (FIG. 4a) which the servo drive uses to measure the motor's angular displacement. As an example, the encoders E1 and E2 have a resolution of about 1,048,576 counts per motor revolution and each motor revolution transports sheets S1-1 and S2-1 150 mm, via left and right side transports 264 and 265. This equates to about 6,990 encoder pulses per millimeter of travel. The servo master controller 135 utilizes this information to cyclically (i.e. a periodic rate) send each servo drive, 137 and 136, a commanded position to achieve the desired position change. The servo drive will then drive the servo motor to the commanded position before the next expected cyclic update. In the hold module 106, a new commanded position is sent to each servo drive at a 1 millisecond (ms) cycle. As an example, the velocity of the left and right side transports 264 and 265 is 5080 mm/sec or 200 in/sec when transporting sheets S1-1 and S1-2 into and out of the hold module 106. To achieve this velocity, the servo master controller 135 increments the commanded position by 35512 each cycle.

$$(D-C) = \frac{\text{Encoder_Counts_Per_Motor_Revolution}}{\text{MM_Per_Motor_Revolution}} \times \frac{\text{Velocity_MM_Per_Second}}{\text{Fieldbus_Updates_Per_Second}}$$

$$(D-C) = \frac{1,048,576}{150} \times \frac{5,080}{1,000}$$

$$(D-C) = 35,512$$

Sheets S1-1 and S2-1 enter the hold module 106 with an initial lead edge alignment A-I introduced by the cutter module 104. A-I can vary between each set of sheets due to slippage in the transfer from the cutter module 104 to the input rollers (293, 294, 297, 298) of the hold module 106. An incomplete cut may require the transport drive to rip the sheet from the cutter, causing a misalignment. Switching from roll to fan fold input paper also can effect alignment. Other reasons for misalignment out of the cutter can occur. However, the current disclosure can correct for the cutter alignment at the completion of every cut. The initial alignment may be a positive or negative. Once sheets S1-1 and S2-1 have been processed through the independent transports 264 and 265, the lead edge alignment A-F has been created between sheets S1-1 and S2-1 which is consistent with the requirements needed to process the sheets in subsequent modules of the inserter 100. The hold module's

106 method of measuring the initial alignment A-I and adjusting the alignment of sheets S1-1 and S2-1 to get alignment A-F is explained in reference to FIGS. 9 through 14.

- 5 Error detection is accomplished upon exiting the hold module 106 by comparing predicted time of arrival with the measured time of arrival of the left and right sheets S1-3 and S2-3 respectively, as measured by photocells 254 and 255, located within idler assemblies 272 and 273 respectively 10 (FIG. 4a). If the measured and predicted time of arrival do not match within a tolerance, an error condition exists that indicates a jam may have occurred in the hold module 106 or the sheet alignment is faulty which may cause a jam in subsequent modules.
- 15 Reference is now directed to FIGS. 5 through 8 for an explanation of how the desired overlap (O-D), for sheets S1-4 and S2-4, required at the TOS 108 exit, is a function of the upstream processes, referencing back to FIG. 4a and the hold module 106 components. FIG. 5 shows left and right 20 sheets S1-1 and S2-1 entering the hold module 106 perfectly aligned (A-I=0). The hold module 106 does not perform any adjustment to the alignment while transporting them to the TOS entry transport 107. Sheets S1-3 and S2-3 remain perfectly aligned prior to entering the TOS 108. The sheets 25 S1-4 and S2-4 then exit the TOS 108 overlapped (S2-4 is on top of S1-4) by distance O-I due to the path length difference through the TOS 108. The amount of overlap (O-I), which is seldom the overlap required by downstream inserter processes, is equal to the sheet length L minus the sheet 30 width W.

$$(O-I)=L-W$$

FIG. 6 illustrates the method employed by conventional systems to produce the desired overlap (O-D) of sheets S1-4 35 and S2-4 at the exit of the TOS 108. Same as FIG. 5, the left and right sheets S1-1 and S2-1 enter the hold module 106 perfectly aligned (A-I=0). Then, while being transported towards the TOS module (108), a method is employed to change the sheet's lead edge alignment to (A-F) prior to 40 entering the TOS 108. This alignment accounts for the TOS module 108 geometry and produces the desired overlap O-D of sheets S1-4 and S2-4 at the TOS exit. For a predetermined desired overlap, required by downstream inserter processes, the necessary change to the sheets lead edge alignment can 45 be calculated.

$$(A-F)=(O-D)-(O-I)$$

Missing from the methods employed in prior art is 50 accounting for the initial alignment A-I that is typically non-zero difference. FIG. 7 illustrates again the method employed by conventional techniques, however with a non-zero initial alignment A-I. In this illustration, sheet S2-1 enters the hold module 106 ahead of sheet S1-1 by a distance A-I. As before, the method to change the sheet's lead edge 55 alignment to A-F is employed however, due to the initial alignment, the sheets enter the TOS 108 with an alignment equal to A-F plus A-I. The overlap of sheets S1-4 and S2-4 at the TOS exit become the desired overlap (O-D) plus the initial alignment (A-I) and thus they are not correctly overlapped for downstream processes. Therefore, a method 60 must be employed to measure the initial alignment (A-I) and account for it in the method employed to adjust the sheet's lead edge alignment to A-F prior to entering the TOS entry transport 107. This is illustrated in FIG. 8, where sheets S1-1 and S2-1 are received with initial alignment A-I. The hold module 106, knowing the initial alignment (A-I), the servo master controller 135, adjusts the alignment by A-C while 65

transporting them to the TOS entry transport **107**. The result is that the sheets **S1-3** and **S2-3** lead edge alignment, prior to entering the TOS **108**, is equal to **A-F** which will result in the correct desired overlap **O-D** between sheets **S1-4** and **S2-4** at the exit of the TOS module **108**.

A unique feature of the hold module **106** of the present application is its ability to measure and account for the initial alignment in the method employed to adjust sheets **S1-1** and **S2-1** lead edge alignment prior to entering a TOS **108**. FIG. 9 illustrates sheets **S1-1** and **S2-1**, with initial alignment **A-I**, in the hold module **106** being transported at a constant and equal velocity towards photocells **252** and **253**, respectively. As explained previously, the constant velocity of sheet **S1-1** and **S2-1** involves the servo master controller **135** cyclically sending the servo drives **136**, **137** a commanded position which is incremented each cycle by **D-C**. To measure the initial alignment (**A-I**), the servo master controller **135** counts the number of encoder pulses received from encoder **E2** from the time sheet **S2-1** triggers photocell **253** until time sheet **S1-1** triggers photocell **252** of servo motor **195** (**E1**). **A-I** is equal to the distance represented by each encoder pulse times the number of encoder pulses received between photocell triggers (FIGS. 10 and 11). **A-I** will be negative if the sheet **S1-2** with the longer travel path (this case the sheet on the right hand side) is trailing sheet **S1-1** upon entering the hold module **106**.

By knowing the initial alignment (**A-I**), the alignment correction (**A-C**) can be accurately calculated so that the sheets enter the TOS module **108** with alignment (**A-F**), to obtain the desired overlap (**O-D**) exiting the TOS module **108**.

$$(A-C) = (A-F) - (A-I)$$

At this point the servo master controller **135** is incrementing both servo drives' commanded position by **D-C** each cyclic update period, thus both sheet **S1-1** and **S2-1** are advanced downstream by the same amount each period. In operation of the present application, the positional control by the servo master controller **135** is utilized to adjust sheets' **S1-1** and **S1-2** alignment to achieve **A-F** prior to entering the TOS **108** by changing the amount by which the servo drive's commanded position is incremented. It is desirable to employ this technique so as to maintain smooth paper handling. The change to the servo drives commanded position incremental value should be minimized. In the hold module **106**, this is done by first dividing the relative amount to adjust (**A-C**) between the two servo drives, retarding one drive by approximately one half **A-C** and advancing the other by approximately one half **A-C**. The error tolerance in the division of the alignment correction **A-C** between transports allows for variation in the one half of **A-C** value from being exactly equal to one half. Second, since it is known that the amount of time the sheets **S1-1** and **S2-1** are within the hold module **106** is greater than one cyclic update period, the adjustment of $\frac{1}{2}$ **A-C** to each servo drive's commanded position is spread out over several updates. The number of cyclic updates (**N**) which adjustment is applied is calculated by dividing the time which it is possible to make this adjustment by the cyclic update period. The allowable time to perform an adjustment (e.g., 42 ms) in the hold module **106** is when sheets **S1-2** and **S2-2** are free of the cutter **104** and the TOS entry transport **107**. The cyclic update period is, for example, 1 ms therefore **N=42**.

The result is that both servo drive's commanded position incremental value at steady state speed (**D-C**) is changed for **N** cyclic updates by:

$$(D-A) = (A-C)/2N$$

Therefore, for **N** cyclic updates, the retarding servo drive's commanded position incremental value (**D-R**) will be equal to **(D-C)-(D-A)** and the advancing servo drive's commanded position incremental value (**D-L**) will be equal to **(D-C)+(D-A)**. FIG. 12 illustrates the sheets position as they move through the hold module **106** and the change in alignment for the first update. The left side transport **264** moves sheet **S1-2** forward by a distance of **(D-R)** and the right side transport moves sheet **S2-2** forward by a distance of **(D-L)**. Subtracting **(D-L)** from **(D-R)**, shows that the net change in the sheets alignment for each cyclic update is $2(D-A)$. Now referring to FIG. 13, after **N** updates the net alignment change is $2N*(D-A)$ which is equivalent to the necessary alignment correction (**A-C**) required, giving initial alignment (**A-I**), to achieve the final alignment (**A-F**) prior to the TOS **108** to get the desired overlap (**O-D**) at the output. The result is that the optimum sheet alignment is achieved without stressing the servo motors or subjecting the sheets to damaging accelerations that can cause jams, slippage and paper damage.

As implemented in the exemplary example, the **D-A** calculation involves returning an integer value however, in this case, if any remainder exists after the division then it is taken into account and handled with an additional fieldbus update. In addition, some of the word usage and such is in reference to a 90 degree left hand turn TOS module **108** configuration. All measurements and calculations work for other configurations, such as the Right Angle Turn (i.e. RAT) used conventionally, as well as initial alignments where sheet **S1-1** is leading sheet **S2-1**.

FIG. 14 is an exemplary process flow chart to illustrate the control steps for the hold module **106**. The control process begins with both servo motors **195** and **196** advancing sheets **S1-1** and **S2-1** at a constant incremental distance (**D-C**) each fieldbus update (S10). Sheets **S1-1** and **S2-1** move from the cutter module **104** into the hold module **106** at a steady state speed as defined by (**D-C**) position updates (S15). Photocells **252** and **253** are used to trigger a read of the value of encoders **E1** and **E2** when sheets **S1-1** and **S2-1** block each photocell **252** and **253** respectively (S20 and S25). In step S30, the initial alignment (**A-I**) of sheets **S1-1** and **S2-1** is calculated based on the values of **E1** and **E2**. In some rare cases, the initial alignment (**A-I**) equals the final alignment (**A-F**) (S35). When this occurs, there is no need to adjust the position update to produce additional offset between sheets **S1-2** and **S2-2**. The servo master controller **135** sends, via cyclic fieldbus communication, the same position update (**D-C**) to each servo motor **195** and **196** (S45).

If (**A-I**) and (**A-F**) are not equal (S35), the alignment correction (**A-C**) is calculated (S40). With the (**A-C**) and (**A-I**) known, the relative change in servo position, per fieldbus command, $2*(D-A)$ required to achieve an Alignment Correction (**A-C**) after **N** field bus cycles may be calculated (step S42). After each servo motor has received **N** cyclic fieldbus position commands, an offset of (**A-C**) in position of sheets **S1-3** and **S2-3** is achieved (S43). The servo master controller **135** then sends (**D-C**) position updates to return sheets **S1-2** and **S2-2** to steady state speed prior to entering the TOS entry transport **107** (S45). The sheets **S1-3** and **S2-3** transfer to TOS entry transport **107** having alignment (**A-F**) (S50). Sheets **S1-3** and **S2-3** are transported from the exit of the hold module **106** to the TOS module **108** via the TOS entry transport **107** (S55). **S1-4** and **S2-4** are merged and overlapped by the desired overlap amount of (**O-D**) in the TOS module **108** (S60), and are ready for continued processing by the inserter system **100**.

11

As shown by the above discussion, functions relating pertain to the operation of an inserting system wherein hold module control is implemented in the hardware and controlled by one or more computers operating as the control processor 130 connected the inserting system and to a data center processor/server 131 for data communication with the processing resources as shown in FIG. 1. Although special purpose devices may be used, such devices also may be implemented using one or more hardware platforms intended to represent a general class of data processing device commonly used to run "server" programming so as to implement the functions discussed above, albeit with an appropriate network connection for data communication.

As known in the data processing and communications arts, a general-purpose computer typically comprises a central processor or other processing device, an internal communication bus, various types of memory or storage media (RAM, ROM, EEPROM, cache memory, disk drives etc.) for code and data storage, and one or more network interface cards or ports for communication purposes. The software functionalities involve programming, including executable code as well as associated stored data. The software code is executable by the general-purpose computer that functions as the control processor 170 and/or the associated terminal device. In operation, the code is stored within the general-purpose computer platform. At other times, however, the software may be stored at other locations and/or transported for loading into the appropriate general-purpose computer system. Execution of such code by a processor of the computer platform enables the platform to implement the methodology for tracking of mail items through a postal authority network with reference to a specific mail target, in essentially the manner performed in the implementations discussed and illustrated herein.

FIGS. 15 and 16 provide functional block diagram illustrations of general purpose computer hardware platforms. FIG. 15 illustrates a network or host computer platform, as may typically be used to implement a server. FIG. 16 depicts a computer with user interface elements, as may be used to implement a personal computer or other type of work station or terminal device, although the computer of FIG. 16 may also act as a server if appropriately programmed. It is believed that those skilled in the art are familiar with the structure, programming and general operation of such computer equipment and, as a result, the drawings should be self-explanatory.

For example, control processor 130 may be a PC based implementation of a central control processing system like that of FIG. 16, or may be implemented on a platform configured as a central or host computer or server like that of FIG. 15. Such a system typically contains a central processing unit (CPU), memories and an interconnect bus. The CPU may contain a single microprocessor (e.g. a Pentium microprocessor), or it may contain a plurality of microprocessors for configuring the CPU as a multi-processor system. The memories include a main memory, such as a dynamic random access memory (DRAM) and cache, as well as a read only memory, such as a PROM, an EPROM, a FLASH-EPROM or the like. The system memories also include one or more mass storage devices such as various disk drives, tape drives, etc.

In operation, the main memory stores at least portions of instructions for execution by the CPU and data for processing in accord with the executed instructions, for example, as uploaded from mass storage. The mass storage may include one or more magnetic disk or tape drives or optical disk drives, for storing data and instructions for use by CPU. For

12

example, at least one mass storage system in the form of a disk drive or tape drive, stores the operating system and various application software. The mass storage within the computer system may also include one or more drives for various portable media, such as a floppy disk, a compact disc read only memory (CD-ROM), or an integrated circuit non-volatile memory adapter (i.e. PC-MCIA adapter) to input and output data and code to and from the computer system.

10 The system also includes one or more input/output interfaces for communications, shown by way of example as an interface for data communications with one or more other processing systems. Although not shown, one or more such interfaces may enable communications via a network, e.g., to enable sending and receiving instructions electronically. The physical communication links may be optical, wired, or wireless.

15 The computer system may further include appropriate input/output ports for interconnection with a display and a keyboard serving as the respective user interface for the processor/controller. For example, a printer control computer in a document factory may include a graphics subsystem to drive the output display. The output display, for example, may include a cathode ray tube (CRT) display, or a liquid crystal display (LCD) or other type of display device. The input control devices for such an implementation of the system would include the keyboard for inputting alphanumeric and other key information. The input control devices for the system may further include a cursor control device (not shown), such as a mouse, a touchpad, a trackball, stylus, or cursor direction keys. The links of the peripherals to the system may be wired connections or use wireless communications.

20 The computer system runs a variety of applications programs and stores data, enabling one or more interactions via the user interface provided, and/or over a network to implement the desired processing, in this case, including those for tracking of mail items through a postal authority network with reference to a specific mail target, as discussed above.

25 The components contained in the computer system are those typically found in general purpose computer systems. Although summarized in the discussion above mainly as a PC type implementation, those skilled in the art will recognize that the class of applicable computer systems also encompasses systems used as host computers, servers, workstations, network terminals, and the like. In fact, these components are intended to represent a broad category of such computer components that are well known in the art. The present examples are not limited to any one network or computing infrastructure model—i.e., peer-to-peer, client server, distributed, etc.

30 Hence aspects of the techniques discussed herein encompass hardware and programmed equipment for controlling the relevant document processing as well as software programming, for controlling the relevant functions. A software or program product, which may be referred to as a "program article of manufacture" may take the form of code or executable instructions for causing a computer or other programmable equipment to perform the relevant data processing steps, where the code or instructions are carried by or otherwise embodied in a medium readable by a computer or other machine. Instructions or code for implementing such operations may be in the form of computer instruction in any form (e.g., source code, object code, interpreted code, etc.) stored in or carried by any readable medium.

35 Such a program article or product therefore takes the form of executable code and/or associated data that is carried on

13

or embodied in a type of machine readable medium. "Storage" type media include any or all of the memory of the computers, processors or the like, or associated modules thereof, such as various semiconductor memories, tape drives, disk drives and the like, which may provide non-transitory storage at any time for the software programming. All or portions of the software may at times be communicated through the Internet or various other telecommunication networks. Such communications, for example, may enable loading of the relevant software from one computer or processor into another, for example, from a management server or host computer into the image processor and comparator. Thus, another type of media that may bear the software elements includes optical, electrical and electromagnetic waves, such as used across physical interfaces between local devices, through wired and optical landline networks and over various air-links. The physical elements that carry such waves, such as wired or wireless links, optical links or the like, also may be considered as media bearing the software. As used herein, unless restricted to non-transitory, tangible "storage" media, terms such as computer or machine "readable medium" refer to any medium that participates in providing instructions to a processor for execution.

Hence, a machine readable medium may take many forms, including but not limited to, a tangible storage medium, a carrier wave medium or physical transmission medium. Non-volatile storage media include, for example, optical or magnetic disks, such as any of the storage devices in any computer(s) or the like. Volatile storage media include dynamic memory, such as main memory of such a computer platform. Tangible transmission media include coaxial cables; copper wire and fiber optics, including the wires that comprise a bus within a computer system. Carrier-wave transmission media can take the form of electric or electromagnetic signals, or acoustic or light waves such as those generated during radio frequency (RF) and infrared (IR) data communications. Common forms of computer-readable media therefore include for example: a floppy disk, a flexible disk, hard disk, magnetic tape, any other magnetic medium, a CD-ROM, DVD or DVD-ROM, any other optical medium, punch cards paper tape, any other physical storage medium with patterns of holes, a RAM, a PROM and EPROM, a FLASH-EPROM, any other memory chip or cartridge, a carrier wave transporting data or instructions, cables or links transporting such a carrier wave, or any other medium from which a computer can read programming code and/or data. Many of these forms of computer readable media may be involved in carrying one or more sequences of one or more instructions to a processor for execution.

In the detailed description above, numerous specific details are set forth by way of examples in order to provide a thorough understanding of the relevant teachings. However, it should be apparent to those skilled in the art that the present teachings may be practiced without such details. In other instances, well known methods, procedures, components, and software have been described at a relatively high-level, without detail, in order to avoid unnecessarily obscuring aspects of the present teachings.

What is claimed:

1. An inserting system configured to adjust alignment of a plurality of sheets of paper outputted from a cutter module, the inserting system comprising:
a hold module positioned downstream from the cutter module, the hold module including:
a plurality of parallel sheet transports for transporting the sheets of paper in parallel;

14

a plurality of servo motors configured to drive each sheet transport and each servo motor coupled to an encoder configured to generate encoder pulses for each rotation of the servo motors;

5 first and second photo sensors configured to detect a presence of first and second sheets at respective sheet transport entry points; and

an inserter system control computer programmed to calculate an alignment adjustment of the sheets in the hold module to account for requirements of one or more modules downstream of the hold module, the system control computer configured to:

calculate an initial alignment offset between the sheets based on a difference in encoder pulses received between a first detection of the first sheet by the first photo sensor on a first sheet transport and a detection of the second sheet by the second photo sensor on a second sheet transport,

receive established sheet alignment requirements of the one or more modules downstream of the hold module,

calculate an alignment correction distance, and control a distance that each sheet in the hold module is

to be moved for each cyclic update.

2. The inserting system of claim 1, wherein the first and second sheet transports are separately driven by first and second servo motors respectively.

3. The inserting system of claim 1, further comprising: a servo master controller associated with the inserter system control computer, the servo master controller is configured to send a different position update to each of the first and second sheet transports for each cyclic update.

4. The inserting system of claim 3, wherein sheet position commands from the servo master controller for the first or second sheet transport feeding a downstream module with a path length longer than a path length of another downstream module is greater than a cyclic position update for a steady state transport position update prior to entering the one or more modules downstream of the hold module.

5. The inserting system of claim 3, wherein sheet position commands from the servo master controller for the first or second sheet transport feeding a downstream module with a path length shorter than a path length of another downstream module is less than a cyclic position update for a steady state transport position update prior to entering the one or more modules downstream of the hold module.

6. The inserting system of claim 1, wherein the one or more modules downstream of the hold module include: an accumulator, folder, or turnover sequencer.

7. The inserting system of claim 6, wherein the calculated alignment correction distance is divided between the first and second sheet transports prior to the first and second sheets entering the one or more modules downstream of the hold module.

8. The inserting system of claim 7, wherein the calculated alignment correction distance is divided equally between first and second servo motors of the plurality of servo motors, such that the first servo motor is retarded by approximately one half and the second servo motor is advanced by approximately one half.

9. The inserting system of claim 1, wherein the alignment correction distance necessary to obtain a final alignment offset required by the one or more modules downstream of the hold module is a function of: an initial measured

15

alignment offset at an input to the hold module and an offset required by the one or more modules downstream of the hold module.

10. The inserting system of claim 1, wherein a number of cyclic updates over which the calculated alignment correction distance is applied is calculated by dividing a time by which it is possible to make the correction by the cyclic update period.

11. A method for aligning a plurality of sheets processed in parallel by an inserter system, the method comprising steps of:

transporting first and second sheets through parallel first and second sheet transports of a hold module of the inserter system;

receiving photocell triggers from first and second photocells, and encoder pulse values from first and second encoders positioned at the first and second sheet transports in the hold module as the first and second sheets are transported through the hold module;

calculating an initial alignment offset by counting a number of encoder pulses received from the first encoder from a first time at which the first sheet triggers the first photocell until a second time at which the second sheet triggers the second photocell;

dividing an amount of alignment correction between a first servo motor associated with the first sheet transport and a second servo motor associated with the second sheet transport based on requirements of one or more subsequent modules downstream from the hold module; and

driving the first servo motor to adjust a first distance moved by the first sheet in the first sheet transport for each cyclic update, and driving the second servo motor to adjust a second distance moved by the second sheet in the second sheet transport for each cyclic update, wherein a total number of cyclic updates sent to each servo motor results in moving the first and second

10

15

20

25

30

35

16

sheets through the hold module while imparting an offset distance between the first and second sheets.

12. The method according to claim 11, wherein the driving of the first and second servo motors imparts a sheet offset required by one or more modules downstream of the hold module, which include: an accumulator, folder, or turnover sequencer.

13. The method according to claim 11, wherein: each cyclic update includes transport servo motor position commands sent from a servo master controller for the first or second sheet transport, and the position commands for the sheet transport that contains the sheet that trails in a final offset are less than the cyclic position commands for a steady state.

14. The method according to claim 11, wherein transport servo motor position commands are sent from a servo master controller for the first or second sheet transport, and the cyclic position commands for the sheet transport that contains a sheet that leads in a final offset are greater than the cyclic position commands for a steady state.

15. The method according to claim 11, wherein the alignment correction sent to the first and second servo motors is divided equally between the first and second servo motors, such that the first servo motor is retarded by approximately one half and the second servo motor is advanced by approximately one half.

16. The method according to claim 11, wherein a total position update, associated with the alignment correction sent to the servo motor drives for the first and second transport servo motors, is divided by a number of cyclic position updates that occur while imparting an offset distance between the first and second sheets.

17. The method according to claim 11, wherein the calculated offset between the first and second sheet imparted by the hold module is a function of the requirements of the one or more modules downstream of the hold module, which include: an accumulator, folder, or turnover sequencer.
